UNITED STATES PATENT OFFICE.

JULIUS A. HEINZ, OF SPRINGFIELD, MASSACHUSETTS.

WASHER-CUTTER.

SPECIFICATION forming part of Letters Patent No. 633,316, dated September 19, 1899.

Application filed December 1, 1898. Serial No. 697,998. (No model.)

To all whom it may concern:

Be it known that I, JULIUS A. HEINZ, a citizen of the United States, residing at Springfield, in the county of Hampden and State of Massachusetts, have invented a new and useful Improvement in Washer-Cutters, which improvement is fully set forth in the following specification and shown in the accompanying drawings.

10 My invention is a device for cutting a number of concentric washers simultaneously out of leather or similar material as by means of a blow of a heavy hammer or a stamp motion of a suitable operating-machine.

15 The object of the invention is to provide a convenient tool or device to be held in the hand or inserted in a machine for quickly forming at one action a plurality of washers, means being provided for conveniently forcing out or discharging the formed washers from the cutter.

20 The invention is hereinafter fully described, and more particularly pointed out in the claims.

25 Referring to the drawings, Figure 1 is an elevation of the device when made in the form of a hand-tool. Fig. 2 is an axial section of the head of the device taken on the dotted line 2 2 in Fig. 3, uncovering the interior parts, parts being shown in two positions by full and dotted lines. Fig. 3 is a lower end view seen as indicated by arrow 3 in Fig. 2. Fig. 4 is an axial section of parts taken on the dotted line 4 4 in Fig. 3. Fig. 5 is a 30 view of the hollow head of the device, seen as indicated by arrow 3 in Fig. 2, the interior parts being omitted. Fig. 6 is a plan of the upper face of the cutter, indicated by arrow 6 in Fig. 2. Fig. 7 is an axial section of 35 the cutter taken on the dotted line 7 7 in Fig. 6, the discharger being shown in two positions by full and dotted lines. Fig. 8 shows a set of rings or washers as produced by the device. Fig. 1 is drawn to a scale one-half that 40 of the other figures.

45 Referring to the drawings, A is the body of the device, it being of iron and formed with a hollow head B.

C is a circular steel cutter for forming the 50 washers a b c, Fig. 8, from a sheet of material E, Fig. 4, of india-rubber, leather, or similar material. The lower part of the cavity

D in the head B is circular and formed to receive the cutter C, above which the cavity is reduced in width, as shown in Figs. 4 and 5. 55 The upper surface of the cutter is straight or flat, as shown in Figs. 4 and 6, bearing directly against transverse surfaces or shoulders d d of the head B, being held to place by simple retaining-screws e e. The lower or 60 working face of the cutter is formed with a series of circular concentric cutting edges 1 2 3 4, Figs. 3, 4, and 7, separated by annular grooves or spaces h i k and a central space l. These cutting edges have diameters according to the sizes of the washers required, each cutting edge serving to form one edge of a 65 washer.

The device is shown as a hand-tool, and in using it it is placed with the cutting edges 70 against the sheet E of material from which the washers are to be cut and struck upon the upper end a blow with a heavy hammer. This drives the cutter through the material, as shown in Fig. 4, separating the washers 75 from the original sheet and from each other, the sheet resting upon a block of wood or other suitable backing during the operation. When the cutter is thus driven through the sheet of material and the washers formed, 80 they stick or hold in the grooves between the cutters from friction and require to be forced out or discharged therefrom. To accomplish this, I provide a discharger F, formed of a bar or head f, and a row of tines or teeth rigid 85 therein extending vertically down through circular openings m, Figs. 3, 6, and 7, through the cutter C. The head f is transverse in the head B and occupies the narrow part of the space D above the cutter, its position being 90 diametrical in the head B. The holes m in the cutter are longitudinal and formed in a diametrical row, as shown in Fig. 6, the outer tines g g being in position to project downward into the space h of the cutter at opposite sides. The next inner tines n n are in position to project into the space i, the tines o o projecting into the space k, and the tine p into the middle space l, said tine p being in the axis of the cutter and the body A. 95

To operate the discharger, I employ a transverse shaft G, provided with a cam or eccentric H, Figs. 2 and 4, to bear upon the upper surface of the head f. An external handle I

of any desirable form is secured to one projecting end of the shaft G, by means of which to operate the latter. The discharger is adapted to move in longitudinal directions in the head B, and if the parts are in the relative positions shown in Figs. 2, 4, and 7 and the handle be turned the discharger will be forced downward, as indicated by dotted positions. This will cause the lower flat ends of the tines to encounter the various washers and throw them out from the cutter, the middle tine p pushing out the center piece u. To hold the discharger normally upward out of the way of the washers while being formed, 15 two spiral lifting-springs r r, Fig. 7, are employed, coiled around the tines o o in enlarged cavities s s, Figs. 6 and 7, in the upper side of the cutter C. When the discharger is pushed downward by the cam to force the washers out of the cutter, said discharger moves against the action of the lifting-springs r r. These springs hold the head f of the discharger normally up against the shoulders t t of the head B, as appears in Figs. 2 and 4. 25 As shown in Fig. 2, the cam H turns through less than a half-revolution to throw the washers out of the cutter. The limit of the motion of the discharger is between the shoulders t t above and the surface of the cutter C below, 30 the proportion of the parts being such that the washers are discharged before the head f encounters the cutter. Now the cam when down being in the position shown by the dotted circle, the springs r r serve to force it back 35 to its normal position without the aid of the attendant—that is to say, when the attendant has forced out the cut washers in any given case he merely releases the handle, giving the parts up to the control of the springs, 40 which serve to return all the moving parts to their normal positions.

For forming washers of different diameters—external and internal—differently-formed cutters are provided to place in the head B, dischargers of differently-arranged tines being provided when necessary.

What I claim as my invention is—

1. A non-rotating washer-cutter consisting of a body having a hollow head, and a cutter in the hollow of said head, the cutter being a single piece and formed with a series of concentric cutting edges each a continuous or unbroken circle, substantially as shown and described.
- 55 2. A device for cutting washers, consisting of a hollow body, and a removable cutter in said body, in a single piece, formed with a se-

ries of circular concentric cutting edges, and a discharger for the cutter, substantially as described.

60

3. A device of the kind described, consisting of a body formed with a cavity, and a removable cutter in said cavity, the cutter being in a single piece and formed with concentric grooves and separate cutting edges, and a discharger for said cutter, having tines to enter said grooves from above the cutter, and means for operating said discharger, substantially as described.

65

4. A washer-cutting device having a cavity, and a cutter in said cavity, the latter having a reduced part, and a discharger for the washers occupying said reduced part of the cavity, the discharger consisting of a head and tines rigid therein and extending through openings in the cutter, and a cam in said cavity to actuate the discharger, and means to operate the cam, substantially as and for the purpose specified.

70

5. A device of the kind described, having a body formed with a cavity, a cutter in the cavity and a discharger in said cavity above the cutter, the body having shoulders to engage the cutter, and other shoulders t t to control the discharger, there being springs in the cutter to actuate the discharger and move it against the shoulders t t, and means to move the discharger against the spring, substantially as shown and described.

75

6. A device of the kind described, formed with a hollow head, and a cutter therein having a diametrical row of longitudinal holes, and a discharger in said hollow head formed with a head-bar provided with a series of tines occupying said holes in the cutter, and means to move said tines in longitudinal directions in said cutter, substantially as specified.

80

7. A washer-cutter consisting of a hollow body and a cutter therein rigid with the body, a discharger in the body, above the cutter, a cam adapted to turn on an axis in the hollow body to actuate the discharger, and springs held by the cutter to control the discharger and the cam, substantially as shown and described.

85

In witness whereof I have hereunto set my hand, this 21st day of November, 1898, in the presence of two subscribing witnesses.

JULIUS A. HEINZ.
